UNITED STATES PATENT OFFICE.

GEORGE P. TILTON, OF NEWBURYPORT, MASSACHUSETTS, ASSIGNOR TO
THE TOWLE MANUFACTURING COMPANY, OF SAME PLACE.

DESIGN FOR A SPOON.

SPECIFICATION forming part of Design No. 20,734, dated May 19, 1891.

Application filed April 18, 1891. Serial No. 389,510. Term of patent 7 years.

To all whom it may concern:

Be it known that I, GEORGE P. TILTON, of Newburyport, Massachusetts, have invented a Design for Spoons, of which the following 5 is a full, clear, and exact description.

Reference is to be had to the accompanying drawing, forming a part of this specification, in which the figure represents a face view of a spoon embodying my new design.

- 10 The design consists in the ornamentation shown, and comprises the handle ornamentation and the bowl ornamentation. The handle ornamentation consists of the figure *a*, representing "Columbus" as standing on a 15 shore and bearing aloft a flag with one hand. The minor features of the handle ornamentation include a sword *b* in one hand of the

figure *a*, a ribbon figure *c*, bearing the inscription "Landing of Columbus, 1492," and the figure *d*, representing a rope ranging longitudinally at the base of the handle and looped adjacent to the bowl. The inscription mentioned forms no part of the design. The bowl ornamentation comprises the representation of three caravels *e*, having their sails 20 set, one of said caravels appearing in advance of the others.

I claim—

The design for spoons herein shown and described.

GEO. P. TILTON.
